(57) CLAIM

The ornamental design for a utensil and paper towel holder, as shown and described.

DESCRIPTION

FIG. 1 is a perspective view of a utensil and paper towel holder, showing my new design;

FIG. 2 is a rear elevational view thereof;

FIG. 3 is a front elevational view thereof;

FIG. 4 is a top plan view thereof;

FIG. 5 is a bottom plan view thereof; and,

FIG. 6 is a right-side elevational view thereof, the left-side elevational view being a mirror image thereof.

The broken lines showing a portion of a barbecue, a paper towel roll and utensils in FIG. 1 depict environmental matter and form no part of the claimed design.
